Luther V. Moulton

ATTORNEY

UNITED STATES PATENT OFFICE.

CHARLES L. FROST, OF GRAND RAPIDS, MICHIGAN.

SPRING-LATCH.

1,075,028.

Specification of Letters Patent.

Patented Oct. 7, 1913.

Application filed January 17, 1913. Serial No. 742,610.

To all whom it may concern:

Be it known that I, CHARLES L. FROST, a citizen of the United States of America, residing at Grand Rapids, in the county of Kent and State of Michigan, have invented 5 certain new and useful Improvements in Spring-Latches; and I do hereby declare the following to be a full, clear, and exact description of the invention, such as will enable others skilled in the art to which it 10 appertains to make and use the same.

My invention relates to improvements in spring latches and its object is to provide the device with various new and useful features as hereinafter more fully described and particularly pointed out in the claims.

This invention relates more particularly to that type of latch having a spring actuated bolt provided with a rounded or conical end and adapted to yieldably engage a recess in a strike plate and to be forced back into the housing to enter and to be removed from the same by the cam action of the rounded or conical end of the bolt.

Referring to the accompanying drawings which illustrate the preferred form of my device:—Figure 1 is a sectional view of a simple form of latch embodying my invention shown in operative position in a door; Fig. 2 is an elevation of the same removed from the door; Fig. 3 is a sectional elevation of a modified form of latch which embodies the essential features of my invention; Fig. 4 a transverse section on the line 4—4 of Fig. 3; Fig. 5 is a plan view of the latch shown in Fig. 3; Fig. 6 is a sectional elevation of another modified form of the latch as adapted for cast metal construction and Fig. 7 is a transverse section on the line 40 7—7 of Fig. 6.

Like numbers refer to like parts in all of the figures.

1 represents tubular housing for a bolt 2; this housing is preferably formed of metallic tube and is closed at one end preferably by recessing the end thereof and turning the remaining portions inward, and in the form illustrated in Figs. 1 and 2, the opposite end is provided with an outturned flange. The 45 bolt 2 is adapted to be inserted in the open end of the housing and slidably therein, being reduced in diameter to form an annular groove 3 around its inner portion, and having its outer end conical or rounded and 50 adapted to project from the housing when in operative position, a coiled spring 4 is

inserted in the housing and bears against the closed end thereof at one end, and thrusts the bolt outward. The bolt is limited in this movement by an inturned portion 5 of the metal forming the wall of the housing, which is bent into the annular groove 3 which groove is of suitable width to permit the bolt to properly move inward in the casing after the same has been inserted in position.

In its simplest form, the three parts enumerated and described above, complete the latch and in operation the housing is simply inserted in a round hole 6 in the edge of the 60 door 7 and an out-turned flange surrounding the open end of the housing engages the surface of the edge of the door and prevents the housing from entering too deeply.

In operation, when the door is finally 65 closed, the spring actuated bolt will recede into the housing and enter a recess in a strike plate 8 in the door casing 9 and yieldably hold the door in closed position. Outward pressure upon the door causes the outer 70 end of the bolt to cam the same inward and remove it from the recess.

Figs. 3, 4 and 5, illustrate more elaborate forms of latches, which embody the essential features of this invention, each being 75 adapted to be attached to the surface of a door. The housing 10 in one modified form, is like the housing, in the simple form, tubular in shape but the edges of the metal which form the tube after being brought together 80 to complete the tube, are turned outward to form base flanges 11 which may be attached to the surface of the door. The rear end of the housing in this form is also closed, but no flange is provided on the open end there- 85 of and the bolt is similar to the one heretofore described and is held in the housing in the same way. This form of latch is also preferably provided with a knob 12 by which the door may be conveniently opened 90 and this knob is preferably mounted on a strip of metal 13, which surrounds the housing and is turned outward over the flanges 11 and held in place by riveting it thereto. To improve the appearance of this latch, 95 the strip 13 is preferably arranged to cover the opening formed by striking in the retainer 5.

Still another modified form of this latch is illustrated in Figs. 6 and 7, and in this 100 form, the housing and bolt which embody the essential features of the invention, are

adapted to be applied to a cast metal case 14. This case is also adapted to be fixed on the surface of a door and is provided with flanges 15 through which screws may be inserted to hold it in place. The case 14 is rectangular in form, being hollow and left open at its inner side and a hole is drilled through the front vertical side thereof and a corresponding recess is drilled into the inner surface of the rear vertical side of the body to receive the housing 16. In this construction the rear end of the housing is not closed, but is inserted in the recess drilled into the rear side of the case and the spring 15 within the housing seats against the bottom of this recess. The outer end of the housing in this form is provided with an out-turned flange, which engages the outer surface of the front side of the case and the housing 20 is held in the case by an out-turned portion 17 of the housing which engages the inner surface of the front of the case, this portion 17 is struck outward after the housing has been inserted in place, and before the bolt 25 has been placed therein. After the housing has been assembled in position, the spring and bolt are inserted and the bolt is retained by striking in a portion of the housing as heretofore described. A knob 18 is also attached to the case preferably by riveting it thereto.

What I claim is:—

1. A latch comprising a tubular housing closed at one end, a bolt slidable in said housing, having an extended groove, a spring behind the bolt engaging the closed end of the housing and yieldably thrusting the bolt outward, and a portion of the wall of the housing struck into the said groove 40 to limit the movement of the bolt.

2. A latch comprising a tubular housing closed at one end, a cylindrical bolt slidable therein, and also having an extended annular groove adapted to project from the housing, the projecting end thereof being conical or rounded, a spring behind said bolt engaging the closed end of the guide and serving to yieldably thrust the bolt outward, and a portion of the wall of the said housing 50 struck into the said groove in the bolt.

3. A latch comprising a tubular housing closed at one end, a spring actuated bolt slidable in said housing and having an elongated annular groove, a portion of the wall 55 of the said housing being struck into the said annular groove to limit the movement of the bolt and an out-turned flange surrounding the open end of the housing.

4. A latch comprising a rectangular hollow case provided with an opening through its forward side and a corresponding recess in the inner surface of the opposite side, said recess being in alinement with said opening, a tubular housing inserted through said opening in the body and into the said recess, a

spring actuated plunger slidable in said housing, and a portion of the wall of said housing being struck outward to engage the inner surface of the forward wall of the case to retain the housing in place. 70

5. A latch comprising a hollow rectangular case having a circular opening through its forward wall and a corresponding recess in the inner surface of the opposite wall, a tubular housing open at its rear end and 75 inserted through the said opening and into the said recess, a portion of the said housing being struck outward to engage the inner surface of the forward wall of the case to retain the housing in position, a bolt 80 slidable in said housing, and a spring behind the bolt engaging the rear end of the same and seating against the bottom of the said recess to yieldably thrust the plunger outward. 85

6. A latch comprising a hollow rectangular case having a circular opening through one of its sides and a corresponding circular recess in the inner surface of the opposite side, a tubular housing open at both 90 ends, inserted through the said opening and into said opposite recess, a portion of the wall of said housing being struck outward to engage the inner surface of the forward side of the case, a cylindrical bolt slidable 95 in the housing and adapted to project from the forward end thereof and having an elongated groove in its body in the said bolt, a spring behind the bolt engaging the rear end thereof and seating against the bottom 100 of the recess in the rear wall of the case, and a portion of the wall of the housing struck inward into the said groove to limit the movement of the bolt.

7. A latch comprising a case formed of 105 sheet metal in the shape of a tubular housing, the edges of said sheet metal being turned outward to form base flanges and the rear of said tubular housing being closed, a spring actuated bolt having a groove 110 therein and slidable in said housing and normally extending outward therefrom, and a portion of the wall of said housing struck inward into the said groove.

8. A latch comprising a case of sheet 115 metal formed in the shape of a tubular housing, the edges of said metal being turned outward to form base flanges and the rear end of said housing being closed, a cylindrical bolt having an annular groove 120 in its body and slidable in said housing and also adapted to project from the forward end thereof, a spring behind the bolt engaging the rear end of the same, and seating against the closed end of the housing and 125 yieldably thrusting the bolt outward, and a portion of the wall of the housing struck inward into the annular groove in the bolt.

9. A latch comprising a case of sheet metal formed in the shape of a tubular hous- 130

ing, the edges of the sheet metal being turned outward to form base flanges, and the rear end of said housing being closed, a spring actuated bolt having an annular groove in its body and slidable in the said housing, and also adapted to project from the forward end thereof, a portion of the housing struck inward into the said groove to limit the movement of the bolt, a strip of metal surrounding the said housing turned outward upon said base flanges, and riveted thereto, said strip of metal being arranged to cover the opening formed by striking inward of the metal therefrom, and a knob attached to the said strip of metal. 15
In testimony whereof I affix my signature in presence of two witnesses.

CHARLES L. FROST.
